UNITED STATES PATENT OFFICE.

MUERK E. WHITE, OF HIGH POINT, NORTH CAROLINA, ASSIGNOR OF ONE-HALF TO
GEORGE W. FLEMING, OF CLINTON, NORTH CAROLINA.

CUSHION.

Application filed December 1, 1925. Serial No. 72,501.

This invention relates to cushions for automobile seats and also for domestic and other uses.

The primary object of the invention is to provide a cushion of the pneumatic type which is so constructed as to regularly distribute or equalize the weight pressure imposed thereon when in use, and also to overcome deficiencies of cushions as found in this type now commonly used.

A further object of the invention is to provide an improved cushion having a strong and durable structure and composed of parts made of rubber compound fabric and rubber over which is applied a suitable upholstery covering or enclosure.

A further object of the invention is to provide a cushion having structural means to prevent distortion thereof when in use and equalize wear on the cushion and also sustain the weight of an individual with equality and comfort.

With the foregoing and other objects and advantages in view, the invention consists in the construction and arrangement of the several parts which will be more fully hereinafter described and claimed.

In the drawings:

Fig. 1 is a top plan view of a cushion for use in automobiles and other vehicles and embodying the features of the invention, the cushion being shown broken away in part and portions thereof illustrated by dotted lines.

Fig. 2 is a bottom plan view of the improved cushion shown broken away and partially in section.

Fig. 3 is a central longitudinal vertical section of the cushion.

Fig. 4 is a transverse vertical section of the same.

Fig. 5 is an enlarged section on the line 5—5, Fig. 3.

Fig. 6 is a view taken on the plane of the line of section 6—6, Fig. 7, and illustrating part of the upholstery covering broken away and the body of the cushion partly in horizontal section, and showing a modification thereof for domestic and general use.

Fig. 7 is a central longitudinal vertical section of the cushion shown by Fig. 6.

Fig. 8 is a transverse vertical section on the line 8—8, Fig. 7.

The body of the improved cushion as shown by Figs. 1 to 5, inclusive, comprises

a top 5 and bottom 6, spaced apart a suitable distance in accordance with the general proportions and dimensions of the cushion and preferably formed from a composite rubber fabric similar to that used in making casings of automobile tires, and extending from the opposite end and side edges of the top 5 is a side and end rubber enclosure or web 7, the upper edges of this enclosure or web being secured to the end and side edges of the top 5 by vulcanization as at 8. The enclosure or web 7, where it is attached to the top 5, forms a flush joint with the latter, and the bottom of this web or enclosure is turned under the end and side edge portions of the bottom 6 and secured by vulcanization as at 9. In addition the body has around and secured to the upper extremity of the enclosure or web 7 a fabric attaching strip 10, which normally projects over the ends and sides of the body a suitable distance. The bottom 6 has an upper frame 11 applied thereto, and to this frame 11 is secured a frame 12, both frames being preferably of wood and having side bars 14 and central, longitudinal and transverse brace bars 15 and 16. Each of the frames are of the same general structure, and between the frame 11 and the bottom 6 the lower terminal edge of the enclosure or web 7 is secured, the said terminal being turned in as clearly shown by Fig. 3. Centrally dividing the body is a rubber partition 17, which extends from the top surface of the bottom 6 to a cross member 18, secured transversely in the top 5. The partition 17 will yield when the cushion is compressed and extends fully transversely across the body and forms two noncommunicating chambers 19 and 20, each of which has an air valve 21 opening thereinto. The cross member or strip 18 is secured to the top 5 by vulcanization and the lower edge of the partition 17 is also secured, preferably by vulcanization, to the center of the top portion of the bottom 6.

Over the body as just described an upholstering covering is applied and consists of a top piece 22, which is secured at its end and side edges to the normally projecting free portion of the fabric strip 10, and to this strip the remaining portion of the upholstering covering is connected and consists of end and side strips 23 and 24, which have their upper edges turned inwardly and

secured to the end and side edges of the piece 22 and then drawn downwardly and secured between the bottom frame 12 and the upper frame 11, as at 24. When the side and end strips or pieces 23 and 24 are drawn downwardly, considerable tension is exerted thereon and this tension results in also drawing down the end and side edges of the top piece 22 and the free projecting edge or portion of the fabric strip 10, so that a rolled seam is provided around the cushion at the sides and ends thereof. After the lower end and side edges of the side and end pieces or strips 23 and 24 are inserted between the bottom frame 12 and the upper frame 11, which form the base or supporting structure of the cushion, the said frame 12 is secured to the frame 11 and at the same time the lower terminal edges of the end strips or pieces 23 and 24 and the lower edge of the enclosure or web 7 are all further secured by inserting screws or analogous fastening devices 25 through these several parts. The air valves 21 project outwardly through the end strips or pieces 23 and are accessible from the exterior of the upholstering covering for application thereto of an air pump or other means for charging the chambers or cells 19 and 20 with air under pressure that will operate to sustain the weight of the user of the cushion, and it will be understood that the amount of air introduced will be proportionate to a certain maximum weight pressure but at the same time the cushion top will be permitted to yield sufficiently to accord comfort to the person who may be using the same. By interposing the partition 17 in the cushion as hereinbefore specified, the air in the chambers or cells 19 and 20 will be confined to comparatively small enclosing areas, and by this means distortion or irregular depression of the cushion when weight pressure is imposed thereon will be obviated. When the cushion is used, the partition 17, being of rubber, will yield without resistance or will not interpose any rigid obstruction at the transverse center of the cushion. The end and side strips or pieces 23 and 24 may be composed of one or more sections of an upholstering covering and the color and pattern of the same may be varied indefinitely. It will also be understood that by interposing the rubber enclosure or web 7 between the top 5 and the bottom 6, which are of stiffer or less yielding material, the cushion at the sides and ends will also yield, and the side and end rubber enclosures or webs as well as the partition 17, being of rubber, will tend, when the cushion is relieved of pressure, to resume their normal positions or restore the cushion to its normal shape. At any time found necessary the air charge of the chambers or cells 19 and 20 may be replenished and the cushion maintained in proper form.

Figs. 6, 7 and 8 show a modification of the cushion, or a cushion that is adapted for domestic and other uses, and while this modified form of cushion is shown as being of rectangular contour, it may be of any shape desired and varied in proportions and general dimensions. In this modified structure the body comprises a bottom 26, which is of the same structure or material as the bottom 6 heretofore described, but in this form of the cushion the top 27 and ends and sides 28 and 29 are formed of rubber, the said ends and sides being preferably of continuous formation with the top 27. Furthermore, the partition 17 heretofore described is eliminated, but adjacent to the end and side portions of the top, or where the latter is turned over to form the ends and sides around the body, a fabric securing strip 30, in all respects similar to the strip 10 shown in the first form of the cushion, is attached, the edge portion of the strip 30 being projected beyond the top 27 a sufficient distance to serve as a securing means for the top piece 31 and end and side piece 32 of the upholstering covering, the end and side strip 32 being continued into or having a bottom piece 33 secured thereto, so that this modified form of the cushion is fully encased by upholstering material. The lower edge of the end and side portions 28 and 29 are secured against the end and side edge portions of the bottom 26 by vulcanization as at 33^a. In this form of the cushion, also, a single chamber or air cell 34 is provided, and at one end of the cushion is an air valve 35, adapted to be connected with a pump or other suitable means for charging the cell 34 with air as found necessary. It will be seen that this modified form of the cushion provides a very compact and durable seat for general use or service, and distortion thereof will be prevented by the air charge within the chamber or cell 34, but at the same time the cushion will have a yielding movement sufficient to render the same comfortable as a supporting means.

The fabric strip 10 as disclosed by Figs. 1 to 5, inclusive, and the corresponding strip 30 illustrated by Figs. 6 to 8, inclusive, is an advantageous feature of the present improvement in that it serves as a convenient means for applying the upholstering covering over the top and at the sides and ends of the cushion in its two forms and also operates to maintain the top covering piece 22 in proper stressed condition relatively to the top of the body of the cushion. This strip also provides means for permitting the side and end portions of the upholstering to be drawn with sufficient tautness over the corresponding parts of the body to form a neat finish and a practical attaching means which will avoid the necessity of puncturing the parts of the body over which the upholster-

ing covering is applied, in view of the fact that the body, in accordance with the features of the invention, should be preserved in air-tight condition in order to render the

- 5 same effective as a storage means for air under pressure. Moreover, by providing the securing fabric strips 10 and 30 and drawing them over the upper portions of the body, the upper corner or bent portions of the body
- 10 are protected by an extra thickness of material produced by the jointure of the upholstering pieces and overlap of the latter with relation to the said securing strip.

What is claimed as new is:

- 15 1. A seat cushion of the class specified, comprising a chambered body to receive air under pressure and having a top and bottom spaced apart and formed of a composite rubber fabric, a rubber web extending from the 20 opposite end and side edges of the top and secured to the latter by vulcanization and forming a flush joint with the said composite top, the rubber web extending around and secured to the bottom of the body, a fabric 25 strip attached to the end and side portions of the top of the body, and an upholstering covering comprising top and side and end pieces having their edges fastened to said strip, the end and side portions of the 30 upholstering covering also being extended under the bottom of the body.

- 2. A seat cushion of the class specified, comprising a chambered body having top, bottom, end and side portions serving as 35 enclosing means for the chamber, the top and bottom of the body being formed of composite rubber fabric and the sides and ends being a rubber strip secured by vulcanization flush with the top of the body and 40 also secured to the bottom of the latter, a fabric securing strip fastened to the end and side edge portions of the top and normally having the outer edge thereof projecting loosely beyond the said latter portions, and 45 an upholstering covering for the body having a top piece attached to said strip and the remaining portion of the covering attached to the edges of the top and the strip to maintain the said covering in proper 50 stressed condition, the strip with the edge portions of the upholstering covering forming a protecting means over the upper edge portions of the body of the cushion.

- 55 3. A seat cushion of the class specified, comprising a chambered body for receiving

air under pressure, the top and bottom body members being yieldable and composed of composite rubber fabric to equally distribute the weight pressure and avoid distortion, a strip being secured to the top and bottom of the body member and forming the sides and ends of the said body, a fabric securing strip fastened to the top and extending partially over the latter and having its outer edge projecting beyond the ends and sides of the body, and an upholstering covering having a top piece attached to the outer normally free edge of the said strip, the remaining portion of the covering being attached to the end and side edge portions of the said top piece and to the strip and tautly drawn over the end and side portions of the body.

4. In a cushion of the class specified, a chambered body to receive air under pressure, said body having top and bottom members composed of rubber compound fabric, the side and end portions of the body being formed of rubber and continued from and vulcanized flush with the top of the body and secured under the edge portions of the bottom member of the body, and an upholstering covering having a fastening means at the end and side edge portions of the top and enclosing the said top and side and end portions of the body.

5. In a cushion of the class specified, a body comprising top and bottom members formed of rubber fabric compound and spaced apart, end and side closing webs vulcanized and secured to the top and flush with the latter and also secured against the bottom of the body and formed of rubber, a central yielding imperforate partition extending transversely with relation to the body and secured to the top and bottom members and thereby forming chambers to receive air under compression, an upholstering covering secured over the top member of the body and also over the end and side web portions and attached under the bottom member of the body, air valves extending through the end portions of the web and upholstering and communicating with the chambers, and bottom frames secured to the bottom member of the body and enclosing the lower edges of the said web and also the lower edges of the upholstering covering.

In testimony whereof I have hereunto set my hand.

MUERK E. WHITE.
